UNITED STATES PATENT OFFICE.

FRANK M. POWELL, OF CHICAGO, ILLINOIS.

DESIGN FOR PRINTING-TYPE.

SPECIFICATION forming part of Design No. 16,870, dated August 24, 1886.

Application filed June 29, 1886. Serial No. 206,658. Term of patent 14 years.

To all whom it may concern:

Be it known that I, FRANK M. POWELL, a citizen of the United States, residing at Chicago, in the county of Cook and State of Illinois, have invented and produced a new and useful Design for Ornamental Printing-Type, of which the following is a specification, reference being had to the accompanying drawing, forming a part thereof.

10 The drawing illustrates a number of different letters embodying my design.

This invention relates to a design for printing-type the face whereof is of an ornamental character; and it consists in repetitions of a 15 cross-pattee covering said face. The particular form is a cross-pattee, the face of each letter being ornamented with repetitions of the same in accordance with the size and the con-

traction and expansion of the same, as shown in the different styles of letters in the drawing.

a represents the cross, the inner ends of the arms being narrow at their junction, while the outer ends are broader, the crosses being arranged in the manner shown—that is, with a 25 perceptible space between each one required to make up the face of the type.

I claim—

The design for ornamental type, consisting of a cross-pattee, the face of each letter being 30 ornamented with repetitions of the same, substantially as herein shown and described.

FRANK M. POWELL.
